Fig. 6

FIGURE 1 is a perspective view of the outside of a bathroom unit embodying my new design.

FIGURE 2 is a general perspective view of the inside of the bathroom looking towards the wash basin.

FIGURE 3 is another perspective view of the inside of the bathroom looking towards the wash basin.

FIGURE 4 is a perspective view of the bathroom looking towards the bath.

FIGURE 5 is a perspective view of the lower part of the bath.

FIGURE 6 is a perspective view of the lower part of the bath viewed from inside the bath alcove from that end of the alcove shown in FIGURE 5.

FIGURE 7 is a perspective view of the lower part of the bath showing that end of the bath alcove opposite to that shown in FIGURE 5.

FIGURE 8 is a general view of the inside of the bathroom looking towards the door.

The characteristic features of my design reside in the interior of the bathroom unit as shown in FIGS. 2 through 8.

This application is a continuation-in-part of my co-pending application D.82,851, filed Dec. 1, 1964, now abandoned.

I claim:

The ornamental design for a bathroom unit, as shown and described.
